CLAIM

The ornamental design for a bend rule, as shown and described.

DESCRIPTION

FIG. 1 is a perspective view of a bend rule showing the design;

FIG. 2 is an alternative perspective view of the bend rule shown in FIG. 1;

FIG. 3 is a top plan view thereof;

FIG. 4 is a front elevational view thereof;

FIG. 5 is a bottom plan view thereof;

FIG. 6 is a back elevational view thereof; and,
FIG. 7 is an end elevational view thereof, the other end being identical.

The broken line showing is for illustrative purposes only and forms no part of the claimed design.
